UNITED STATES PATENT OFFICE

2,610,666

BENDING MACHINE

Harold A. Thompson, Silverton, Oreg.

Application June 27, 1950, Serial No. 170,608

2 Claims.

(Cl. 153—15)

1

This invention relates to bending machines and is particularly adapted for bending of flat metal bars and the like.

The primary object of the invention is to provide a bar bending machine for bending flat metal bars of any thickness by interchanging simple removable bending anvils within the bending machine without the use of tools.

With my new and improved bending machine, various thicknesses of flat bars can be bent at a sharp angle, or they may be bent with more or less of a radius bend by simply changing the removable bending anvils.

The thicker the bar to be bent the less number of bending anvils that will be required to bend the same, or by adding or removing some of the anvils with a given thickness of bar a bend of varying radii may be made.

A further object of my invention is to provide a simple bending tool that can be mounted on a bench having few parts, requiring no tools for adapting the same to the various thickness of flat bars to be bent.

These and other incidental objects will be apparent in the drawings, specification and claims.

Referring to the drawings:

Figure 1 is a perspective view of my new and improved bending machine in partial exploded view.

Figure 2 is a plan sectional view of Figure 1, taken on line 2—2.

Figure 3 is a plan view of Figure 1.

Figure 4 is a side sectional view, taken on line 4—4 of Figure 3.

Figure 5 is a side sectional view, taken through Figure 3 on line 5—5 and on line 5—5 of Figure 2.

Figure 6 is a perspective view of the bending anvil removed from the bending machine, the handle partially broken away.

Referring more specifically to the drawings:

The bending machine comprises a base 1, having a working surface with a bearing opening 8 recessed therein, and two spaced-apart stationary vertically disposed angular shaped anvils 2 and 3 welded in place as at 4.

5 indicates a rotary bending member. This member consists of a disk 6 and a semi-disk 7 and an intermediate bending anvil. The disk 6 is journaled in the bearing opening 8, while the bending anvil is in cooperative relation with the fixed anvils 2 and 3. The bending anvil is disposed with its apex in alignment with the axis of said disk 6, and said semi-disk 7 has a flat edge 16 that is coplanar with one surface of said anvil as best shown in Figure 6.

6 is a semi-disk journaled within a bearing 9 formed by a segmental portion 10, welded at 11 to the top of the fixed anvil 2, and a segmental portion 12 spaced from the portion 10 and which is integral with the fixed anvil 3 and an arcuate portion 14 on a removable ring 13.

The semi-disk 7 is journaled within a bearing 9 formed by a segmental portion 10, welded at 11 to the top of the fixed anvil 2, and a segmental portion 12 spaced from the portion 10 and which is integral with the fixed anvil 3 and an arcuate portion 14 on a removable ring 13.

The removable ring 13 surrounds the segmental portions 10 and 12, with its arcuate portion 14 filling the gap between said two portions

10 and 12.

The purpose of this structure is to provide a space when the ring 13 is removed to place a flat bar to be bent between the anvils 2 and 3, or remove said bar after bending. By removing the

ring 13 and aligning the flat edge 16 of the semi-disk 7, the bar to be bent will pass down through the space 17 between the segments 10 and 12 of the bearing 9 and past the flat edge 16 of the semi-disk 7, and past the side of the bending

anvil 5 to the bases. When the ring 13 is replaced, it completes the raceway for receiving the semi-disk 7 and confines the bar between the two anvils 2 and 3.

The purpose of this structure is to provide a space when the ring 13 is removed to place a flat bar to be bent between the anvils 2 and 3, or remove said bar after bending. By removing the

ring 13 and aligning the flat edge 16 of the semi-disk 7, the bar to be bent will pass down through the space 17 between the segments 10 and 12 of the bearing 9 and past the flat edge 16 of the semi-disk 7, and past the side of the bending

anvil 5 to the bases. When the ring 13 is replaced, it completes the raceway for receiving the semi-disk 7 and confines the bar between the two anvils 2 and 3.

The purpose of this structure is to provide a space when the ring 13 is removed to place a flat bar to be bent between the anvils 2 and 3, or remove said bar after bending. By removing the

ring 13 and aligning the flat edge 16 of the semi-disk 7, the bar to be bent will pass down through the space 17 between the segments 10 and 12 of the bearing 9 and past the flat edge 16 of the semi-disk 7, and past the side of the bending

anvil 5 to the bases. When the ring 13 is replaced, it completes the raceway for receiving the semi-disk 7 and confines the bar between the two anvils 2 and 3.

It will be noted that the semi-disk 7 engages the segment 10 and pushes against the same in the bending operation, as shown in Figure 3.

The bearing surface of arcuate portion 14 is co-radial with the inner bearing surfaces of the bearing ring segments 10 and 12.

In the operation of my new and improved

bending machine, the ring 13 is removed as illustrated in Figure 1. This permits the insertion of the bar 18 to be bent. Removable anvils 19 are placed between the anvil 3 and the bar, the number or size of anvils placed therebetween will

more or less determine the radius that the bar is to be bent.

The handle 20, which is fixedly secured to the bending element 5, is then moved in the direction of the arrow 21, which will bend the bar 18 at 22

against the anvils 19. The amount that the bar will be bent can be determined by the scale markings 23. After said bar is bent, the ring 13 is removed as shown in Figure 1, permitting the bar to be removed from the bender.

One of the outstanding features of my bending machine, is the rigidity of structure as well as its simplicity, having the bending element mounted

between two rigid bearings, one in the base plate and the upper bearing, which is mounted rigidly to the upper ends of the anvils. Further, this upper bearing can be dismantled, permitting the

insertion and removal of the object to be bent, and the provision of auxiliary bending anvils for forming the desired bends on the object to be bent.

These anvils are always handy, as they are supported by the vertically mounted angle 24, which is welded to the base 1 and the upstanding pin 25, which receives and holds the auxiliary anvils 19 in place for easy access in the bending operation.

Although certain specific modifications of the invention have been shown and described, it is obvious that many modifications thereof are possible. The invention, therefore, is not to be restricted except in so far as is necessitated by the prior art and by the spirit of the appended claims.

What I claim is:

1. A bending apparatus comprising a base 15 having a horizontally disposed working surface with a bearing recessed therein, a pair of spaced angular anvils fixed to said base and extending upwardly from said working surface adjacent said bearing, a bending member including a disc 20 journaled in said bearing and carrying a vertically disposed angular bending anvil in cooperative relation with said pair of anvils for bending a metal strip, and a handle extending from said bending member for pivoting said disc to swing said bending anvil relative to said pair of anvils, a semi-disc fixed to the top of said bending anvil, said semi-disc having a diametrical edge that is

coplanar with one surface of said bending anvil to enable insertion of a metal strip past said diametrical edge and between said anvils, and a ring removably mounted on said pair of anvils and having a bearing portion for journailling said semi-disc, whereby said ring may be removed for insertion of a metal strip between said anvils.

2. A bending apparatus as defined in claim 1 wherein a pair of ring segments are respectively fixed on the tops of said pair of anvils and are surrounded by said bearing ring, the inner surfaces of said segments forming bearing surfaces for said semi-disc, the bearing portion of said ring extending between said segments and having a bearing surface co-radial with said segment bearing surfaces.
